ATTORNEYS

UNITED STATES PATENT OFFICE.

ALBERT J. LEWIS, OF BURR OAK, MICHIGAN.

WIRE-SPlicing TOOL OR WRENCH.

Application filed January 21, 1926. Serial No. 82,706.

The object of the invention is to provide a very simple and efficient tool for splicing wire.

Objects relating to details and economies 5 of construction and operation of my invention will definitely appear from the detailed description to follow.

The invention is defined and pointed out in the claim.

10 A structure which is a preferred embodiment of my invention is clearly illustrated in the accompanying drawing, forming a part of this application, in which:

15 Fig. 1 is a detail view of my improved wire splicing wrench or tool in use, the tensioning means and wire clamp with which it is used being shown in dotted lines;

20 Fig. 2 is a side elevation of my improved tool substantially full size, the ratchet teeth, pawl and spring being indicated by dotted lines;

25 Fig. 3 is a detail view of the head with one side removed, appearing substantially as a section on line 3—3 of Fig. 4, with the twisting head and the actuating dog and spring in full lines;

Fig. 4 is a sectional view taken on line 4—4 of Figs. 2 and 3;

30 Fig. 5 is a transverse detail sectional view taken on line 5—5 of Figs. 3 and 4, showing the pawl, spring, and retaining means;

Fig. 6 is a detail view of the meeting ends of the wire inserted into the double tubular connector; and

35 Fig. 7 shows the same after it has been twisted by my improved wire splicer and the splice completed.

The parts of the drawing will be referred to by their numbers, which identify like 40 parts in all the views.

Referring to the drawing, 1 is the double handle made of symmetrical corresponding plates, offset at 11, 11 into separated sides or cheek pieces 13, 13, which are adapted 45 to embrace the hub of the revolving wire twisting head, being radially open at 14 at the outer end. These plates are retained together by suitable rivets or screws 12. Between these parts is retained the revolving twisting head 2 provided with a hub 21 on each side with peripherally projecting ratchet teeth 22. A radial slot 23 extends

to the center where there is formed a seat 24 conformed to receive a double tubular wire splice. The sides of the handle embrace the hubs and head so that it is held under slight friction and the handle can be readily revolved about it to rotate the same for twisting the splice.

A dog or pawl 3 is provided for this purpose which is pivoted on the cross pivot 31, provided with an engaging tooth 32 corresponding to the ratchet teeth 22 on the head. A projecting thumb piece 33 at the side of the handle facilitates manipulation 65 of the tool. A spring 4 with cross head 41 engaged in apertures 42 in the cheek pieces 13 holds the dog yieldingly in engagement with the ratchet teeth.

The tool is a special tool for splicing 70 wire. The wires are tensioned by the usual puller devices, indicated by dotted lines in Fig. 1, and the ends of the wire 5 are inserted in the tubular connector 6 and are 75 grasped by a wire clamp. My improved tool is then brought into action by slipping it over the wire and sliding it endwise onto the double wire connector in proximity to the clamp. The tool is then rotated by operating the handle ratchet-wise. When the 80 splice has been completed and the tool has passed off from the connector the dog 3 is depressed to free the head and the tool is 85 pulled off the wire, thus bringing the head with its radial slot to the precisely correct position in the cheek pieces for future use. The dog is released and the head is thus held so that there is no need for adjusting the twisting head in the tool.

I am aware that ratchet heads have been 90 variously held for various purposes and I do not wish to be understood as claiming the same broadly. I wish to claim the feature that cooperates with the connector by 95 sliding action.

Having thus described my invention, what I claim as new and desire to secure by Letters Patent, is:

In a wire splicing tool or wrench for applying a splice sleeve connector to wires, 100 the combination of a handle made up of symmetrical sides with head embracing portions open at the outer ends, a twisting head with hubs extending into said embracing

portions provided with a ratchet at its periphery and a radial slot to cooperate with said open head embracing means, said slot being enlarged into engaging slots at its inner end to slide lengthwise of a connector sleeve, a pawl or dog pivoted between the sides of said handle with a laterally

projecting thumb piece, and a spring for holding the same into engagement with the ratchet wheel, coacting substantially as described for the purpose specified.

In witness whereof I have hereunto set my hand.

ALBERT J. LEWIS.
